UNITED STATES PATENT OFFICE.

OTTO BANNER, OF EASTON, PENNSYLVANIA, ASSIGNOR TO INGERSOLL-RAND COMPANY, OF JERSEY CITY, NEW JERSEY, A CORPORATION OF NEW JERSEY.

BLADING CONSTRUCTION FOR TURBO-COMPRESSOR IMPELLERS.

1,071,660.

Specification of Letters Patent.

Patented Aug. 26, 1913.

Application filed October 25, 1912. Serial No. 727,651.

To all whom it may concern:

Be it known that I, OTTO BANNER, a subject of the German Emperor, residing at Easton, in the county of Northampton and 5 State of Pennsylvania, have invented a certain new and useful Improvement in Blading Construction for Turbo-Compressor Impellers, of which the following is a specification.

10 This invention relates to turbo compressor impellers and more particularly to the blading of such impellers.

In the construction of turbo compressor impellers a common form of blading is that 15 which consists of a piece of sheet metal the edges of which are bent over at right angles to form flanges which are pivoted to the disk and cover of the impeller. In practice it has been found however that the great 20 centrifugal strain causes such blades to give way near the edges at their outer ends with the result that semicircular pieces are detached bodily from the ends of the blades impairing the efficiency of the impeller and 25 throwing it out of balance.

The object of the present invention is to 30 prevent such breaking of the blades and this is accomplished, broadly speaking, by making the blades in two parts, the inner portion where there is comparatively little strain being made of the usual bent sheet material and the outer part of a separate 35 piece of stronger material which is usually incapable of being bent and must be milled into shape, a process which if applied to the whole blade would make the cost prohibitive.

Practical embodiments of this idea are shown in the accompanying drawings in which,

40 Figure 1 shows a section of an impeller embodying my blading with the cover partly broken away, Fig. 2 shows a section on the line 11-11 of Fig. 1, and Figs. 3-6 show modified forms of the blading.

45 The impeller as shown in Figs. 1 and 2 comprises a disk 1 and cover 2. Between these are secured the blades which consist of inner portions 3 made of sheet metal with flanges 4 bent at right angles and secured 50 to the disk and cover by rivets 5, and outer portions 6 made somewhat in the shape of an I beam with flanges 7 and 8 secured to the disk and cover by rivets 9. This outer portion of the blade is preferably made of a

strong steel which can not be bent and hence 55 must be milled into shape. The center of the blade at the end is made thinner to lessen the centrifugal stress on the blade which makes itself felt most strongly on each side of the blade close to the disk. 60

In Fig. 3 a form is shown wherein the outer portion 6 is made of a heavier piece and is secured to the disk and cover by rivets passing through it. In this form the inner end of the part 6 is riveted to the outer end 65 of the inner part 3. In Fig. 4 a similar form is shown wherein the part 6 has flanges to secure it to the disk and cover and is also riveted to the outer end of the part 3.

In Figs. 5 and 6 a form is shown similar 70 to Fig. 1 but provided with longitudinal strengthening ribs 10 extending along one face of the blade.

It is to be understood that the present 75 showing and description discloses only certain specified modifications of my invention and other forms and modifications are included in the spirit and scope of the invention as expressed in the claims.

What I claim is:

1. In a turbo compressor, a disk, a cover, and blades between said disk and cover said blades comprising an inner part secured to said disk and cover and a separate outer part having flanges thereon secured to said 85 disk and cover.

2. In a turbo compressor, a disk, a cover, and blades between said disk and cover, said blades comprising an inner part secured to said disk and cover and an outer part secured to said disk and cover forming a continuation of the inner part, said outer part being of stronger material than said inner part. 90

3. In a turbo compressor, a disk, a cover, 95 and blades between said disk and cover, said blades comprising an inner part having bent flanges secured to said disk and cover and an outer part secured to said disk and cover forming a continuation of the inner part, said outer part being of stronger material than said inner part.

4. In a turbo compressor, a disk, a cover, and blades between said disk and cover, said blades each comprising an inner part having 105 bent flanges secured to said disk and cover and an outer part having flanges secured to the disk and cover, said outer part forming

a continuation of the inner part and being of an unbendable material stronger than said inner part.

5. In a turbo compressor, a disk, a cover, and blades between said disk and cover, said blades each comprising an inner part having bent flanges secured to said disk and cover and an outer part having flanges secured to the disk and cover, and longitudinal ribs,

said outer part forming a continuation of the inner part and being of an unbendable material stronger than said inner part.

In testimony whereof, I have hereunto set my hand:

OTTO BANNER.
